UNITED STATES PATENT OFFICE.

EVERETT J. COOK, OF TOLEDO, OHIO.

DESIGN FOR A FRONT END FOR MOTOR-VEHICLES.

46,200.

Specification for Design.

Patented Aug. 4, 1914.

Application filed May 21, 1914. Serial No. 840,132. Term of patent 7 years.

To all whom it may concern:

Be it known that I, EVERETT J. COOK, a citizen of the United States of America, residing at Toledo, Lucas county, Ohio, have invented a new, original, and ornamental Design for Front Ends for Motor-Vehicles, of which the following is a specification, reference being had to the accompanying drawing, forming part thereof.

Figure 1 is a front perspective view look-

ing a little down on the motor vehicle front end, and Fig. 2 is a side elevation thereof, showing my new design.

I claim:

The ornamental design for a front end for motor vehicles, substantially as shown.

EVERETT J. COOK.
